PROJECTILE

Frank J. Fuller, 6217 Chadwick Ave., San Diego, Calif.
Filed May 14, 1962, Ser. No. 194,389

1 Claim. (Cl. 102—38)

The present invention relates to a projectile and more particularly to one which is fired from a gun barrel.

The projectile of the present invention is elongated and has the shape of an angle in cross section at right angles to the elongation or linear direction thereof. In the preferred embodiment, the elongated projectile has the shape of a right angle in cross section at right angles to the linear direction thereof. Too, in the preferred embodiment, the front of the side walls of the projectile angle rearwardly from adjacent the front portion of the crest formed by these side walls.

Further features and the advantages will be apparent from the following description, reference being had to the accompanying drawing wherin a preferred embodiment of the invention is illustrated.

In the drawing:

FIG. 1 is a perspective view of the projectile.

FIG. 2 is a top plan view of the projectile.

FIG. 3 is a side view of the projectile and the cartridge case therefor, the cartridge case being shown in cross section.

FIG. 4 is a front view of the projectile and cartridge case.

FIG. 5 is a rear view of the projectile removed from the cartridge case, and

FIG. 6 is a cross sectional view of the gun barrel used in the present invention.

Referring more in detail to the drawing, the elongated projectile is shown at 20. It is angular in cross section, including two side walls 22 and 24, the crest of which is indicated at 26. The fronts of the side walls angle rearwardly from adjacent the front portion of the crest as shown at 28, to form a blunt nose 30 as shown in FIG. 1, or from the crest to provide a pointed front 32 as shown in FIGS. 2 and 3. Preferably, the side walls 22 and 24 are at right angles and, in cross section, simulates an angle iron.

2

Of course, the gun barrel must have an elongated rectangular passage therein. Such gun barrel is shown at 34 and the conforming passage is shown at 36.

The cartridge case for the projectile is shown at 38. The rear end 40 can be cylindrical, and then the forward end is crimped to conform with the angular outside periphery of the projectile, and to closely embrace the inner surfaces of the walls 22 and 24.

The present invention has the advantage of maintaining a flatter trajectory or shorter ordinate in flight with less propelling powder, and is not materially affected by windage.

While the form of embodiment herein shown and described constitutes preferred form, it is to be understood that other forms may be adopted falling within the scope of the claim that follows.

I claim:

In combination, a cartridge case and an elongated projectile having the shape of an angle iron in cross section at right angles to the linear direction thereof, the fronts of the side walls thereof angle rearwardly from adjacent the front portion of the crest thereof, and the rear end of said projectile extending into the cartridge case, said cartridge case closely embracing said rear end.
